UNITED STATES PATENT OFFICE.

SIDNEY C. HOWARD, OF COLUMBUS, OHIO.

OIL CONTROL AND OIL-FEEDER.

1,401,081.

Specification of Letters Patent. Patented Dec. 20, 1921.

Application filed November 6, 1920. Serial No. 422,283.

To all whom it may concern:

Be it known that I, SIDNEY C. HOWARD, a citizen of the United States, residing at Columbus, in the county of Franklin and 5 State of Ohio, have invented a new and useful Oil Control and Oil-Feeder, of which the following is a specification.

This invention relates to internal combustion engines, and more particularly to the 10 lubricating system thereof, it being the primary object of the invention to provide novel means for feeding lubricating oil to the crank casing of the motor, whereby the lubricating oil is maintained at predetermined levels.

A further object of the invention is to provide an operating means in connection 15 with the usual throttle rod so that the supply of oil to the crank casing is automatically controlled with the movement of the throttle rod.

A still further object of the invention is the provision of means for replenishing the 20 quantity of oil within the crank casing as the same is being used.

With the foregoing and other objects in view which will appear as the description 25 proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the invention.

The figure illustrates a sectional view 35 through the elements of the system, and showing the same as applied to a crank casing.

Referring to the drawing in detail, the system is shown as applied to a crank casting 40 in which the oil level is indicated by the reference character 6, the oil level in the crank casting as shown being the desired maximum level of the oil for the efficient running of the motor at all times.

The system includes a supply tank 7 which is supported in any convenient location 45 adjacent to the motor associated therewith, and as shown this tank is provided with a filling opening 8 which is closed by the plug 9 that is of a construction to insure an air-tight connection between the

plug and tank, eliminating any possibility 55 of air entering through the top of the tank.

The lower portion of the tank 7 is secured to the coupling 10 as by means of the securing member 11, which is provided with a central bore 12 establishing communication 60 between the tank 7 and coupling 10, there being provided however a spring pressed ball valve 13 operating within the coupling, for closing one end of the bore 12 to hold the oil within the tank 7, as the tank is being filled. Carried by the plug 9 is a rod 14 which is designed to engage the ball valve 13 and unseat the same against the tension of the coiled spring 15 associated with the ball valve, thereby permitting the oil within the 70 tank 7 to pass through the coupling 10.

Associated with the tank 7 is a feed tank 16 which has a threaded portion 17 to receive the threaded portion of the adjustable head 18 and through which head passes a feed 75 pipe 19, the same being carried by the head and designed to move therewith. It is obvious that by rotating the head 17, the pipe 19 may be adjusted within the tank 16, for purposes to be hereinafter more fully described.

The pipe 20 provides communication between the coupling 10 and tank 16, so that the oil contained in the tank 7 may be fed to the tank 16 from where the oil passes 85 into the crank casing 5 to supply the engine supported above the crank casing.

Movably supported on the pipe 19 is a controlling tube 21, which is of a diameter to closely fit around the pipe 19 and prevent 90 air from passing to the pipe 19 from a point between the pipe 19 and tube 21. This tube 21 is provided with a circumferential flange 22 which is apertured to accommodate the guide rod 23 that maintains the tube against 95 rotary movement, but permits the same to move vertically in the tank 16, whereby the lower end of the tube 21 may be held at various positions within the tank 16.

An operating rod 23 has connection with 100 the flange 22, the rod 23 being however connected with the usual throttle rod which controls the passage of gas through the carburetor, and which in the present drawing has been omitted, it being understood however that the operating rod 23 moves with the throttle rod to move the tube 21 with respect to the pipe 19.

The pipe 24 provides means of communication between the tank 16 and crank casing 5, so that the oil supported within the tank 16 may flow to the crank casing. It 5 might be further stated however that a drain cock 25 is positioned in the pipe 24, and by means of which the tank 16 may be drained, in the event that it becomes necessary to drain the tank for purposes of 10 repair.

In the operation of the device, the oil level as shown by the drawing, indicates the maximum quantity of oil to be maintained in the crank casing when the engine 15 is running at its maximum speed, the controlling tube 21 is in a position taken when the engine is at a standstill.

Assuming that the engine is started and the throttle is moved to admit gas to the 20 engine to cause the same to speed up, it is obvious that as the throttle rod moves the operating rod 23 is moved to move the controlling tube 21 to a position as indicated in dotted lines. As the oil is consumed by the 25 engine, the oil level in the tank 16 falls, admitting air to the pipe 19 which allows the oil within the tank 7 to flow into the tank 16 until the same closes the end of the pipe 19 within the tank, and the level 30 of the oil within the tank is in the same horizontal plane, with the lower end of the pipe 19.

With the controlling tube 21, in a position as indicated by the drawing, and the engine running at a moderate rate of speed, the oil level within the crank casing 5 may fall to a point in the same horizontal plane with the lower end of the controlling tube 21, whereupon air will enter the tube 21 35 and allow a quantity of oil to flow into the tank 16 and crank casing 5, the quantity of oil at this level being sufficient to permit the efficient running of the engine at a moderate rate of speed.

Having thus described the invention, what is claimed as new is:—

1. In an internal combustion engine having a crank casing, and having a throttle rod controlling the passage of gas to the engine, the combination of an oil supply tank associated with the crank casing, a feed tank associated with the supply tank, and means having connection with the throttle rod and operating within the feed tank for automatically controlling the level of oil within the crank casing.

2. In an internal combustion engine having a throttle rod controlling the passage of gas thereto, the combination of a supply tank, a feed tank in communication with the supply tank and having an adjustable head, a pipe disposed within the feed tank and carried by the adjustable head, said pipe having one end disposed within the supply tank, and means on one end of the pipe for controlling the level of oil within the feed tank, said means being automatically controlled by the operation of the throttle rod.

3. In an internal combustion engine, having a throttle rod controlling the passage of gas therethrough, the combination of a supply tank, a feed tank in communication with the supply tank, a pipe communicating with the tanks, a controlling tube having a flange formed exteriorly thereof, said controlling tube adapted to move over one end of the pipe, means for guiding the controlling tube in its movements, and said flange adapted to lie in a plane with the fluid level in the feed tank.

In testimony that I claim the foregoing as my own, I have hereto affixed my signature in the presence of two witnesses.

SIDNEY C. HOWARD.

Witnesses:

FLOYD C. BARROWS,
Mrs. SIDNEY C. HOWARD.
